UNITED STATES PATENT OFFICE.

BRYNTE BRYNTESON, OF ODEBOLT, IOWA.

AIR-CUSHION FOR PUMP-OPERATING MECHANISM.

1,327,940.

Specification of Letters Patent.

Patented Jan. 13, 1920.

Original application filed June 8, 1918, Serial No. 238,985. Divided and this application filed March 5, 1919.
Serial No. 280,856.

To all whom it may concern:

Be it known that I, BRYNTE BRYNTESON, a citizen of the United States, residing at Odebolt, in the county of Sac and State of Iowa, have invented certain new and useful Improvements in Air-Cushions for Pump-Operating Mechanism, of which the following is a specification.

The invention relates to an air cushion for pump operating mechanism and is a division of an application filed by me June 8, 1918, Serial Number 238,985.

The object of the present invention is to provide a simple, practical and efficient air cushioning device of strong, durable and comparatively inexpensive construction and design for connecting two sections of a reciprocating pump rod and to be interposed between the power or operating mechanism to prevent injury to either mechanism.

With these and other objects in view the invention consists in the construction and novel combination and arrangement of parts hereinafter fully described, illustrated in the accompanying drawings, and pointed out in the claims hereto appended, it being understood that various changes in the form, proportion, size and minor details of construction, within the scope of the appended claims may be resorted to without departing from the spirit or sacrificing any of the advantages of the invention.

In the drawing:

Figure 1 is a side elevation of a cushioning device for pump rods constructed in accordance with this invention.

Fig. 2 is a vertical sectional view of the same.

Fig. 3 is a vertical sectional view of the cushioning device illustrating a slightly different lower pump rod attaching means from that shown in Figs. 1 and 2.

In the accompanying drawing, in which is illustrated the preferred embodiment of the invention, 1 designates a pump rod composed of upper and lower sections 2 and 3 yieldably connected by means of a coiled spring 4 and the air cushioning device 5 to enable the pump rod to be reciprocated through the alternate meshing of the pinions with the master gear as shown in the aforesaid application or with any other operating means, without jarring or injuring the pump or other device operated by the

mechanism and without liability of breaking the pump rod.

The cushioning device 5 comprises a cylinder 6 receiving a piston 7 mounted on the upper section of the pump rod and equipped with a suitable packing 8. The cylinder is provided at its upper end with a head or end wall 9 having a central opening 10 through which passes the upper section 2 of the pump rod or member 1; and the spring 4, which is sleeved on the upper section 65 of the pump rod or member, is interposed between the upper section or member and the cylinder for cushioning the parts, a suitable stop 11, such as a pin or key, being provided to hold the end of the spring. A washer 12 is interposed between the pin or key 11 and the upper end of the spring to form a seat for the latter. The cylinder is provided with an upper guide 13, preferably in the form of a yoke and receiving the upper section of the pump rod. The lower end of the cylinder is provided with a depending portion 14 converged downwardly and suitably secured to the upper end of the lower section 3 of the pump rod 1. The upper and lower sections 2 and 3 of the pump rod are connected by a chain 15 or other suitable flexible connection, which permits a limited independent movement of the parts to enable the cushioning device to perform its function and at the same time provides a positive unyielding connection between the upper and lower sections when the upper section has reached the limit of its independent upward movement.

The blower depending portion 14 which extends from the lower end of the cylinder 6 to the lower section of the pump rod may be in the form of a yoke as illustrated in Fig. 3 of the drawings, but if desired a substantially conical cylinder head 14^a may be provided, as illustrated in Figs. 1 and 2 of the drawings. When the cylinder 6 is equipped with the tapered head 14^a the latter is preferably provided at the top with 100 an annular or cylindrical flange 16 which is threaded on the lower end of the cylinder, as clearly indicated in Fig. 2 of the drawing, and the lower section 3 of the pump rod passes through a tubular portion 17 of the 105 bottom of the inverted conical head 14^a and is secured therein by a clamping screw 18 or other suitable fastening means.

What I claim is:

1. The combination of a reciprocating member composed of upper and lower sections, a flexible connection between the sections to permit limited independent movement thereof and cushioning means comprising a cylinder mounted on one of the sections and a piston operating in the cylinder and carried by the other section of the reciprocating member.
2. The combination of a reciprocating member composed of upper and lower sections, a flexible connection between the sections to permit a limited independent movement thereof and cushioning means comprising a cylinder mounted on one of the sections, a piston operating in the cylinder and carried by the other section of the reciprocating member, an upper guide mounted upon the cylinder and slidably receiving the upper section of the said member, and means depending from the cylinder for connecting the lower section of the member with the same.
3. The combination of a reciprocating member, composed of upper and lower sections, a flexible connection between the sections to permit limited independent movement thereof and cushioning means comprising a cylinder mounted on one of the sec-

tions, a piston operating in the cylinder and carried by the other section of the reciprocating member, and a coiled spring disposed on the upper section and bearing upon the cylinder and arranged to cushion the parts. 35

4. The combination of a reciprocating member, composed of upper and lower sections, a chain connecting the upper and lower sections, a cylinder located above the lower section and provided with an upper end wall having an opening receiving the said upper section of the reciprocating member, said cylinder being opened at the bottom and provided with depending portions secured to the said lower section of the reciprocating member, a piston carried by the upper section of the said member and operating within the cylinder, a guide mounted upon the upper end of the cylinder and composed of spaced sides and a connecting portion having an opening receiving the upper section of the said member, and a coiled spring located within the guide and disposed on the upper section of the said member and arranged to cushion 50 the latter and the cylinder. 55

In testimony whereof I hereunto affix my signature.

BRYNTE BRYNTESON.
